CHRISTOPHER H. SNYDER, OF BERKELEY, CALIFORNIA

BUILDING AND METHOD OF CONSTRUCTING THE SAME

Application filed August 22, 1930. Serial No. 477,065.

This invention relates to buildings and a method of constructing buildings and particularly to improvements which enable buildings comparable to those of the Class A type to be constructed at least as rapidly and with less cost than has been possible heretofore. Buildings of the Class A type are built with a steel frame which carries all horizontal and vertical stresses.

10 Multi-story buildings such as tall office buildings are presently constructed either of steel frame or of reinforced concrete. The steel frame building possesses, among other advantages, the advantage of much quicker 15 erection than the reinforced concrete building. The latter building however, is less costly in construction and is therefore feasible in certain situations where a steel frame building would be uneconomic. The time of 20 erection of a reinforced concrete building is prolonged however, due to the necessity of supporting the forms for each floor, from the concrete floor below, this requiring the setting of the concrete in the lower floor before 25 the concrete can be poured for the floor next above. This delay in waiting for the setting 30 of the concrete, and the necessity for shoring from floor to floor, for the entire height of the building, makes the erection of the concrete building much slower than the erection of the steel frame building.

Reinforced concrete buildings are also limited by building laws to ten or twelve stories in height. The cheapness of their construction is by means of the present invention 35 made available in Class A building construction which is not restricted as to height.

I propose to provide a building which has all of the advantages of the steel frame building, both with respect to stability and speed 40 of erection, and which in addition employs reinforced concrete construction in sufficient magnitude to reduce materially the cost of the building. The concrete is employed in such 45 manner that delays for the setting thereof are not encountered and so that the continuous shoring is eliminated. This I accomplish by constructing, in the preferred form of the invention, each alternate floor of the usual or 50 desired steel frame construction and con-

structing the intermediate floors of reinforced concrete construction, supporting forms for the intermediate concrete floors from the contiguous steel frame floors, thus permitting the building to be erected with the speed of 55 one having a full steel frame, but at a lesser cost.

It is the principal object of the present invention to devise a novel building and method of constructing the same which enables 60 an improved building to be constructed with at least as great a speed and at a lessened cost compared to present buildings and methods of building construction.

Other advantageous features and objects 65 of the invention will appear in the following in which I have outlined the preferred form of building and the method of constructing the same of my invention. It is to be understood that the building and method disclosed are the preferred embodiment and manner of practicing the invention but that modifications and variations herein can be made within the scope of the appended 70 claims. 75

Briefly characterized, the building and the construction method therefor comprise a steel building frame, erected in the usual fashion, the frame including the usual steel columns and steel floor beams, but having the 80 usual superimposed steel floors spaced widely apart as at every alternate floor level or at every third floor level. The absent floors are subsequently built in of reinforced concrete. The forms and other structures necessary for the erection of each concrete floor 85 are supported from an adjacent steel floor as by hanging or shoring. The effect of this manner of construction is to obviate a good portion of the expensive steel beams, for 90 which is substituted the light and comparatively inexpensive re-enforcing rods, and to increase the speed of erection as compared to a reinforced concrete building since all the concrete floors can be constructed simultaneously or as fast as the steel frame is placed. Further, the shoring does not have to be carried up continuously from the ground. 95

In the drawing the single view is a dia- 100 grammatic illustration of a building erected

in accordance with the preferred manner of the present invention. The view particularly depicts a side elevation of a portion of the building.

5 The invention is probably best understood in detail by considering the erection of a building in accordance with the preferred manner. Steel columns 7, designed in a manner usual to any steel frame building, are 10 erected by methods employed by those skilled in that art. A plurality of transverse steel members such as beams are positioned between the columns to provide several spaced superimposed steel floors 8. These floors are 15 preferably spaced apart at a distance greater than the normal distance at which floors are ordinarily provided in a building. Thus, the floors are preferably spaced about 25 feet apart, or twice the normal distance of 12½ 20 feet usually provided between floors, although they can be otherwise spaced as at every third floor level, or 37½ feet apart, or, whatever spacing is required by the architect. The steel floors 8 and the columns 7, 25 together with other steel members usual to construction such as wind bracing and tie members, constitute a steel building frame in which, for example, approximately only half of the number of floors are present. Due 30 to the absence of alternate steel frame floors, the wind bracing members at each steel frame floor may be increased in magnitude, if desired.

35 In accordance with the present invention, the floors omitted between the steel floors are provided of reinforced concrete or of concrete construction with the omission of the usual heavy steel beams, the concrete construction 11 including only the usual reinforcing steel utilized in any materials and such minor beams such as wind bracing desirable from a design standpoint. The floors of reinforced concrete are readily constructed at the desired level in the building by supporting the forms therefor from a contiguous steel floor as from the steel floor below, by shoring, or from the floor above, by hanging. This is quite possible since the design 45 of the steel floors includes a live load factor and a factor for the weight of partitions which loads, until the building is finally completed, are not present. The columns are designed to take the whole weight of the building and no undue weight is therefore 50 placed upon them.

55 The building and method of my invention constitutes a distinct advance in the art over previous buildings and methods inasmuch as it is not necessary to wait for the concrete to 60 set before the next floor can be poured. Since the forms for the reinforced concrete floors are borne by the steel floors, the reinforced concrete floors can be poured as fast as the forms and reinforcing steel are placed and 65 as fast as the steel frame can be erected.

The cheapness of reinforced concrete makes possible a saving at present prices of approximately twenty-five cents for each square foot of reinforced concrete floor employed in the construction. This saving is further apparent when it is considered that the steel beams in say half the floors are replaced by light reinforcing rods which carry the tension and by the concrete which carries the compression. Very little concrete is required for the concrete floors in excess of that ordinarily utilized in fire-proofing the steel beams in steel frame construction.

70 I claim:

75 1. A building comprising upright steel columns, a plurality of steel floor beams fixed on said columns and vertically spaced apart, and a reinforced concrete floor fixed on said columns and disposed in the space between said steel floor beams.

80 2. A building comprising a frame including a plurality of substantially vertical steel columns and a plurality of substantially horizontal steel beam floors supported by said columns, and substantially horizontal reinforced concrete floors located between said steel beam floors and supported by said columns.

85 3. A method of constructing a building comprising erecting a plurality of steel columns, erecting a plurality of spaced steel beam floors supported on said columns, erecting a plurality of removable forms for cast reinforced concrete floors, supporting said forms from said steel beam floors and in the 90 spaces between the latter, and forming said concrete floors in said forms.

95 In testimony whereof, I have hereunto set my hand.

CHRISTOPHER H. SNYDER.
